UNITED STATES PATENT OFFICE

PAUL BURKE, OF GREEN BAY, WISCONSIN, ASSIGNOR TO NORTHWEST ENGINEERING CORPORATION, A CORPORATION OF WISCONSIN

PULL SHOVEL

Application filed June 29, 1927. Serial No. 202,401.

The invention relates to excavating machines and more particularly to shovelling machines of the type in which the shovel or dipper is pulled toward the machine during digging, machines of this type being generally employed for such work as digging ditches.

In my prior United States Patent, No. 1,562,288, dated November 17, 1925, I have shown in Fig. 1 an excavating machine or 10 pull shovel of the type above described in which the pull or drag cable is guided along the boom at a small or negligible distance above the boom hinge and this is the reeving ordinarily used in machines of this type and 15 the only force tending to push the dipper into the work is gravity acting upon the weight of the boom, dipper and dipper stick. As the depth of the digging increases the lifting effect of the drag cable upon the whole 20 assembly becomes more pronounced and as the depth increases a point is reached where additional crowding force is necessary to cause the apparatus to negotiate hard digging successfully. This additional crowding effect 25 may be attained by adding weight to the boom, dipper or dipper stick, this, however, having the great disadvantage of requiring additional energy to hoist and also imposing a more severe requirement upon the 30 braking mechanism in order to lower the added weight back into the trench. To overcome these difficulties without increasing weights I have provided a construction in 35 which the power of the prime mover is used to increase the thrusting effort and more particularly by reeving of the drag cable at either its live or dead end, or both, so as to dispose said cable below the hinge pin of 40 the boom, with the result that the tensioned drag cable creates a downward thrust on the boom and hence on the dipper so that it will negotiate hard digging successfully and have further provided means for increasing this 45 thrusting effect.

The invention further consists in the several features hereinafter set forth and more particularly defined by claims at the conclusion hereof.

50 In the drawings Fig. 1 is an elevation view

of a machine embodying the invention, showing the dragline reeved in one way;

Fig. 2 is a detail plan view of part of the boom and the dragline arrangement shown in Fig. 1;

Fig. 3 is a detail elevation view of the inner end of the boom showing a modified form of reeving of the dragline;

Fig. 4 is a detail plan view of the arrangement shown in Fig. 3;

Fig. 5 is a detail elevation view of the inner end of the boom showing a modification of reeving of the dragline;

Fig. 6 is a detail plan view of the arrangement shown in Fig. 5.

A full side elevation view of the machine is shown in Fig. 1 and as the modifications hereinafter described deal more particularly with the reeving of the dragline at the inner end of the boom the complete machine has 70 not been reproduced as the relation of the parts will be clear from Fig. 1.

In the drawings the numeral 7 designates the boom vertically pivotally attached at its inner end to a hinge-pin 8 suitably mounted 75 on the rotating base 9 of the machine, which base is of well-known construction and mounted on the travelling base 10 of the machine. A prime mover 11 is mounted on the base 9 and through suitable transmission 80 mechanisms drives the propelling treads 12 and actuates the hoisting drum 13 and the dragline drum 14. The drums 13 and 14 may be of any suitable construction equipped 85 with clutches and brakes to control their operation and as shown are axially aligned with each other.

A dipper 15 has its handle 16 pivotally mounted on the outer end portion of the boom at 17 and carries a pair of padlock sheaves 18 (one being shown) at its upper end around which the hoisting cable 19 is wound, as more particularly shown and described in the aforementioned patent, said cable also passing around a sheave 20 secured to an upright frame member 21 and having one end 22 dead-ended on the frame of the machine and the other end passing over a pulley 23 to the drum 13. Thus, by operating 95 100

the hoisting drum the dipper and boom may be raised and lowered.

In Fig. 1 the dragline 24, instanced here as a two-part line, passes from the drum 14 under a sheave 25 mounted on the rotating base adjacent one side of the boom and beneath the hinge-pin 8, thence over sheaves 26 and 27 on said boom, down around a padlock sheave 28 associated with the dipper and thence over a sheave 29 and is dead-ended at 30 upon the boom. With this reeving there is a downward pulling or thrusting moment upon the boom equal to the tension in the drag cable 24 multiplied by the perpendicular distance C between the line of action of said cable at sheave 25 and the center of the hinge-pin 8. Thus, when the boom 7 and dipper 15 have been lowered into digging position, as shown in Fig. 1, and the hoist cable 19 is being payed out as the drag cable is being pulled in the tension of said drag cable will act to pull the boom downwardly and hence increase the crowding effect on the dipper, during digging, over the weight of the boom, dipper and dipper stick or handle. Thus, in this instance, disposing the live end of the drag cable 24 below the boom hinge produces the desired effect.

The same effect may be had by displacing the dead end of the drag cable below the boom hinge, as shown in Figs. 3 and 4 wherein the live end 31 of the dragline passes from the drum 14 under a pulley 32 above the boom hinge 8 and thence over the sheaves 26 and 27, as in the first-described arrangement, around the padlock 28, and the dead end portion 33 of said dragline passes over the sheave 29, journaled on the same shaft as that for the sheave 27, and sheave 34, journaled on the same shaft as that of sheave 26, thence downwardly over a sheave 35 on the boom which, during digging, is below the hinge-pin of the boom, and is dead-ended at 36 on the base 9 of the machine.

An increased digging effect over those described may be had by displacing both the live and dead ends of the drag cable below the boom hinge by a combination of the arrangements shown in Figs. 1 and 3, wherein the live end of the dragline passes from the drum 14 over the sheave 25 and thence over sheaves 26 and 27 to the padlock 28, as shown in Fig. 1, and the dead end portion returns by way of sheaves 29, 34, 35 to the dead end 36, as shown in Fig. 3. This arrangement has not been shown in detail as it is generally similar to that shown in Figs. 4 and 5 which further increases the thrusting effect by running the dead end portion 37 of the dragline over a pulley or sheave 38, mounted on arms 39 secured to the base 9, and dead-ending it at 40 on the boom. This sheave arrangement, including the sheave 38, doubles the thrusting effect of the dead end of the dragline over that shown in Fig. 3.

Aside from the reeving above described, whereby the thrusting effect on the dipper during digging is increased, the general operation of the machine is similar to that of my prior patent, it being noted that the action of the dipper is governed by the manipulation of the hoist and draglines and that after the dipper receives its load the boom is hoisted until the dipper clears the bank and then by swinging the boom, by the turning of the base 15, the dipper is moved to its discharge position at which time the dragline 24 is released or paid out and the weight of the dipper and its contents then swings the dipper outwardly to discharge the load.

Inasmuch as the effectiveness of the drag cable tension to produce the downward crowding effort is proportional to the perpendicular distance between the line of action of the cable and the center of the hinge-pin, an adjustment of this effort may be readily effected by adjusting the placement of the sheaves, such as sheaves 25 or 35, used in guiding the drag cable in the vicinity of the boom hinge-pin, such adjustment obviously providing for the shifting of the shafts for said sheaves on their support, in any suitable manner.

I desire it to be understood that this invention is not to be limited to any particular form or arrangement of parts except insofar as such limitations are included in the claims or necessitated by the prior art.

What I claim as my invention is:

1. In an excavating machine of the type described, the combination with a support, of a boom pivoted thereon, a dipper and dipper handle pivotally carried by the boom and movable toward said support during digging, a hoisting cable associated with the dipper and boom, and a dragline associated with the dipper and means for guiding said dragline along the boom and beneath the same reeved to produce a downward pull on the boom adjacent its pivot to produce a thrusting effort on the dipper.

2. In an excavating machine of the type described, the combination with a support, of a boom pivoted thereon, a dipper and dipper handle pivotally carried by the boom and movable toward said support during digging, a hoisting cable associated with the dipper and boom, and a dragline associated with the dipper and having a portion in thrusting engagement with the boom and having a portion working, during digging, in a plane beneath the boom pivot to produce, with said first named portion, a thrusting effort on the dipper.

3. In an excavating machine of the type described, the combination with a support, of a boom pivoted thereon, a dipper and dipper handle pivotally carried by the boom and movable toward said support during digging, a hoisting cable associated with the dipper and boom, and a multi-part dragline associ-

ated with the dipper and boom and having one of its parts working, during digging, in a plane beneath the boom pivot to produce, with the part associated with the boom, a thrusting effort on the dipper.

5. 4. In an excavating machine of the type described, the combination with a support, of a boom pivoted thereon, a dipper and dipper handle pivotally carried by the boom and movable toward said support during digging, a hoisting cable associated with the dipper and boom, and a two-part dragline associated with the dipper and boom and having its live and dead end portions reeved to work, 10 during digging, in a plane beneath the boom pivot to produce, with the parts associated with the boom, a thrusting effort on the dipper.

5. 5. In an excavating machine of the type described, the combination with a support, of a boom pivoted thereon, a dipper and dipper handle pivotally carried by the boom and movable toward said support during digging, a hoisting cable associated with the dipper and boom, a multi-part dragline associated with the dipper and boom and having one of its parts working, during digging, in a plane beneath the boom pivot to produce, with the parts associated with the boom, a thrusting effort on the dipper, and means associated with said part of said line to increase its thrusting effort.

6. 6. In an excavating machine of the type described, the combination with a support, of a boom pivoted thereon, a dipper and dipper handle pivotally carried by the boom and movable toward said support during digging, a hoisting cable associated with the dipper and boom, a dragline drum on said support, a sheave on the intermediate portion of the boom, a dragline passing from said drum and over said sheave and associated with said dipper, and dragline guide means for depressing a part of said dragline between said drum and sheave to a position below the boom pivot to produce a thrusting effort on said boom and dipper during digging.

7. 7. In an excavating machine of the type described, the combination with a support, of a boom pivoted thereon, a dipper and dipper handle pivotally carried by the boom and movable toward said support during digging, a hoisting cable associated with the dipper and boom, a dragline associated with the dipper and boom and dead-ended at a point adjacent and below the boom pivot to produce, with the part associated with the boom, a thrusting effort on the dipper during digging.

8. 8. In an excavating machine of the type described, the combination with a support, of a boom pivoted thereon, a dipper and dipper handle pivotally carried by the boom and movable toward said support during digging,

a hoisting cable associated with the dipper and boom, and a dragline associated with the dipper, dragline guide means on said boom intermediate its ends, and dragline guide means to dispose a portion of said cable in a plane beneath the boom adjacent its pivot and cooperating with said first-named guide means to produce a thrusting effort on said boom and dipper during digging.

In testimony whereof, I affix my signature. 75
PAUL BURKE.
